UNITED STATES PATENT OFFICE.

ERWIN B. LOEWENBACH, OF MILWAUKEE, WISCONSIN.

STITCH-DOWN SHOE.

Application filed August 21, 1926. Serial No. 130,706.

This invention relates to stitch down shoes.

In stitch down shoes as heretofore constructed, it has been impossible to press the upper inwardly on the inner side of the arch or instep during the formation of the shoe. The result of this has been that there is always a gap left at this point, and subsequent wear of the shoe increases the gap and makes the shoe spread at this point with loss of support to the arch and instep, and also with a material detract from the appearance of the shoe.

This invention is designed to overcome the defects noted above and objects of such invention are to provide a novel form of stitch down shoe which is so constructed that the upper is held inwardly at the inner side of the instep or arch, and the shoe is prevented from spreading, and to provide a construction in which a reenforcing stay secured to the inner side of the upper at the inner portion of the instep is used and acts as a support to the arch and also as a means for insuring the retention of the upper in its correct position, so that a very much more serviceable and comfortable shoe results, together with an increase in the attractiveness of the shoe.

Further objects are to provide a novel form of stitch down shoe in which a tie strap or reenforcing stay is secured to the inner side of the upper adjacent the inner portion of the instep, and is cemented or glued down over the lining after the lining has been placed over the inner sole, so that it strengthens the shoe at the point where the greatest tension occurs, where bending is greatest, and where there is the greatest wear and strain upon the shoe. Further, it is to be noted that in the practice of this invention a cheaper grade of cement may be used to secure the sole in place with consequent saving, as the necessary strength is furnished by the stay strap.

An embodiment of the invention is shown in the accompanying drawings in which:

Figure 1 is a view from the underside of the partially completed shoe with the outer sole removed;

Figure 2 is a side view of the construction shown in Figure 1 with, however, the stay strip shown hanging down before it has been drawn into place;

Figure 3 is a transverse sectional view on the line 3—3 of Figure 1.

In practicing this invention the upper 1 is provided with a lining 2 in the usual manner, and such lining is drawn inwardly over the insole 3, as shown most clearly in Figures 1 and 3. The lining is secured to the inner sole. Further, it is to be particularly noted that a stay strap or reenforcing member 4 which may be of strong fabric, leather, or similar material, is stitched as indicated at 5, to the inner side of the upper 1 adjacent the inner side of the instep or arch. While the shoe is being lasted, this stay strap is cemented down upon the lining and inner sole, and is drawn tightly across the shoe, as shown in Figure 3. If desired, this stay strap may have its end tucked between the upper on the other side of the shoe and the lining or it may stop short of such other side of the shoe. At all events, it is stitched or otherwise rigidly secured to the upper on the inner side of the instep, and is cemented or secured rigidly to the inner sole. Thereafter, the outer sole 7 is secured in place in the usual manner, the upper being turned outwardly, as indicated at 6.

It is to be particularly noted that the term "cementing" is intended to cover cementing, gluing, or other means of fastening.

Further, it is to be noted that the stay strap may be most easily secured to the upper, and during the lasting of the shoe, may be readily drawn tightly across the inner sole and cemented in place. Obviously, the stay strap, as stated, can extend clear across the shoe and between the lining and the upper on the other side of the shoe, or it may extend only part way across the inner sole. It firmly holds the upper inwardly at the inner side of the instep, and permits the accurate and neat finishing of the stitch down shoe in a manner heretofore considered impossible.

Although the stay strap constructed as described, has been found eminently satisfactory, it is to be understood that the stay strap may be made as wide as desired or, in fact, the entire inner portion of the upper may have a reenforcing stay secured thereto and drawn across the inner sole, although as described above, the stay strap constructed as set forth, has been found sufficient.

Further than this, it is to be noted that

the reenforcing strap or stay strip acts as a brace for the shoe and hold its against spreading. It resists the natural wear of the shoe at its point of greatest bending and increases 5 the life of the shoe. In addition to this, it acts as a support for the arch of the foot and prevents the undesirable spreading.

It is to be noted further that although the marked improvements noted above results in 10 the practice of this invention, that it may be carried out with the utmost cheapness and facility and without increasing the cost of the shoe more than a minute amount.

If it should be decided to build an unlined 15 shoe, this invention could be equally well followed. In fact a series of stay strips could be employed either with a lined or unlined shoe and could be located wherever desirable, depending entirely upon the type of shoe.

20 Further, in stitch down shoes as heretofore constructed, the insoles have been relatively wide at the instep and did not properly fit the foot. With this invention, however, the insoles may be made narrow at the instep to 25 accurately fit the foot and the uppers may be easily and permanently drawn inwardly to conform to the cut in insoles.

Although the invention has been described 30 in considerable detail, such description is intended as illustrative rather than limiting as the invention may be variously embodied and as the scope of such invention is to be determined as claimed.

I claim:

35 1. A stitch down shoe comprising an upper, an inner sole and an outer sole, and a stay strip secured to the upper on the inner side of the instep and drawn across the bottom of the inner sole and secured in place.

40 2. A stitch down shoe comprising an upper, an inner sole, a lining carried by said upper and cemented to said inner sole, a stay strip secured to said upper on its inner side and on the inner side of the instep, said stay strip 45 being drawn tightly across the bottom of the inner sole and lining and secured in place,

and an outer sole secured to said upper and enclosing said stay strip between said inner sole and said outer sole.

3. A stitch down shoe comprising an upper, 50 an inner sole reentrant adjacent the inner side of the instep, a stay strip secured to the inner side of the upper at the inner side of the instep and drawn across the inner sole to hold the upper inwardly at the reentrant portion 55 of the inner sole, and an outer sole secured to said upper.

4. A stitch down shoe comprising an upper provided with a lining, an inner sole having 60 the lining cemented thereto, a stay strip 65 stitched to the inner side of the upper on the inner side of the instep and drawn tightly across said inner sole and cemented thereto, and an outer sole secured to said upper and inner sole. 65

5. A stitch down shoe comprising an upper, 70 an inner sole, and an outer sole, and a stay strip secured to said upper and drawn inwardly and secured between said inner and outer soles. 70

6. A stitch down shoe comprising an upper, 75 an inner sole, said upper having outwardly turned marginal edges, a stay strip stitched to the upper adjacent the inner side of the instep and extending across the shoe beneath the inner sole, said inner sole having a reentrant portion adjacent the inner side of the instep, said stay strip being drawn tightly and secured to said inner sole to hold the upper inwardly drawn adjacent the reentrant portion, 80 an outer sole and stitching passing through the outwardly turned portions of the upper and the outer sole, whereby said stay strip is secured to said upper adjacent the inner side of the instep and is secured to the bottom of said inner sole. 85

In testimony that I claim the foregoing I have hereunto set my hand at Milwaukee, in the county of Milwaukee and State of Wisconsin.

ERWIN B. LOEWENBACH.
